UNITED STATES PATENT OFFICE.

ROY M. FORSYTH, OF GOUVERNEUR, NEW YORK, ASSIGNOR OF ONE-HALF TO OTTO E. PATTBERG, OF GOUVERNEUR, NEW YORK.

MOTION-PICTURE APPARATUS.

Application filed March 31, 1923. Serial No. 629,087.

To all whom it may concern:

Be it known that ROY M. FORSYTH, a citizen of the United States, residing at Gouverneur, in the county of Saint Lawrence and State of New York, has invented certain new and useful Improvements in Motion-Picture Apparatus, of which the following is a specification.

This invention relates to motion picture apparatus and particularly to an automatically controlled and operated fire gate which is adapted to be automatically interposed in the path of the rays from the projection lamp, if for any reason the movement of the film across the film opening is stopped.

In carrying out my invention, I utilize the principle involved in a driving mechanism which has been termed a non-positive magnetic-clutch drive, one of the elements of which in the present instance is employed to control an electrical circuit in which is included the fire control gate.

I further employ in my construction, a peculiar form of yielding connection between a film driven friction element which will permit of a substantial constant and interrupted motion in one direction of the permanent magnet of the magnetic-clutch device, although its initial drive is responsive to the intermittent movement of the film.

Various other features, through which I accomplish the results as hereinafter explained, will be self evident to those skilled in the art.

In the accompanying drawings,—

Figure 1 is an elevation of a moving picture machine showing my invention applied thereto.

Figure 2 is a plan view thereof.

Figure 3 is a detail vertical longitudinal sectional view of the various shafts and the members carried thereby.

Figures 4, 5 and 6 illustrate details of construction.

Figure 7 is a diagrammatic view of the electrical wiring.

Figure 8 is a detail transverse sectional view showing the electrical contacts.

Figure 9 is a detail sectional view on the line 9—9 of Figure 1.

Referring now to the drawings by numerals of reference, 2 designates the frame

of a moving picture projecting machine of conventional form, and in which 4 represents the film gate or opening through which the pictures are projected upon the screen; and 6 the fire gate or shutter operable within a guide frame 8, which latter will be described more fully hereinafter.

Mounted upon a convenient part of the front of the machine frame, within bearing sleeves 9 carried at the lower end of a pair of spaced plate springs 10 attached as by screws 11 to said machine frame, is a rotary shaft 12 to which are rigidly fastened by keys or other suitable means, a pair of disks 14, preferably of aluminum, the periphery of each of which is faced with rubber 15 or other friction material, said disks being arranged upon the outside of the bearing sleeves and projecting through the film gate and in operation, in frictional engagement with the film shown at 16 in dotted lines.

Supported upon the front of the machine frame by a pair of bearing sleeves 18, carried by metal plates 19 attached as by screws 20, and in axial alinement with the shaft 12, is a second rotary shaft 22, said shafts 12 and 22 being connected by a coil torsion spring 24, in such manner that rotation of the former imparts a similar movement to the latter. This yielding connection performs a useful function as will be presently described.

The outer end of the second shaft 22 has fixed thereto for rotation therewith a multipolar permanent magnet 26, the hub 28 of which is preferably of aluminum. The outer end of the shaft 22 is further formed into a spindle bearing 30.

Arranged over and concentric with the rotary permanent magnet 26, but in spaced relation thereto, and upon a shaft 32 to which it is fixed, is a drum armature 33, which specifically comprises an outside shell 34 of laminated steel or soft steel having an inner circumferential series of transversely arranged, spaced copper bars 36, the drum being faced upon one side with a copper ring 38, and upon the opposite face with a copper disk 40, and with which latter the shaft 32 is connected.

The shafts 32 and 22 are also in axial alinement, the inner end of the former being

provided with a bearing cup 41 into which is received the spindle bearing 30 of the latter. At its outer end, the shaft 32 has its bearing within the cup 42 of an adjustable bearing screw 44 threaded within a bracket 46 secured as by screws to the front of the machine frame. The arrangement just described produces a construction which may be known as a magnetic clutch, the magnetism of the permanent rotary magnet resulting in a tendency of the surrounding armature drum to rotate or drag with the former, it being understood that due to the air gap between the magnet and armature, there is never a positive connection between the driving and driven members.

Permanently secured at its inner end to the drum shaft 32, is a coiled helical spring 48 carrying at its free end which is arranged 20 on a tangent, an electrical contact 50 which cooperates with a fixed contact 52 carried by but insulated electrically from the machine frame.

When the contacts 50 and 52 are brought 25 into engagement in the manner to be subsequently set forth, an electrical circuit in which the machine frame and a double pole solenoid magnet 54 are included, is completed, thus energizing the spools 56 and 30 drawing within them the cores 60, the latter being bridged by a bar 62.

The bar 62 is connected through a link 64 with one end of a rock arm 66 pivoted at 68 on the machine frame, the opposite end 35 of said arm, through a link 70, supporting the fire-gate 6 which slides within the guide frame 8. A coil tension spring 74 attached at one end to the gate carrying end of the rock arm 66 and at the other end to a fixed 40 part of the machine frame tends to maintain the gate closed in safety position except when the machine is in operation.

While my invention should be readily understood from the foregoing description, 45 especially to those familiar with the art to which this apparatus relates, I will give a brief outline of the manner of operation:

The motion picture machine being in 50 operation, and the film 16 moving downwardly past the projection opening, frictionally contacts at its margins with the friction disks 14 and through the flexible shafting 12 and 22, rotates the permanent magnet 26 dragging the drum armature 33 55 in a counter-clockwise direction, and bringing the contact 50 carried by the spring 48 into engagement with the fixed contact 52 on the machine frame. The closing of these contacts results in the energizing of the 60 solenoid coils 56, attracting the cores 60 and through the link and rocking arm connections 64, 66 and 70 lifting the film gate.

If for any reason, the movement of the film should be interrupted, the contacts 50 65 and 52 will be separated, thus breaking the

circuit and deenergizing the solenoid magnet, and permitting the spring 74 to rock the arm 60 and close the film gate.

From the foregoing description of the construction of my improved apparatus, it 70 will be seen that I have provided a simple, inexpensive and efficient means for carrying out the objects of the invention, and while I have particularly described the elements best adapted to perform the functions set forth, 75 it is obvious that various changes in form, proportion, and in the minor details of construction may be resorted to, without departing from the spirit or sacrificing any of the principles of the invention. 80

I claim:

1. In a fire trap operating mechanism for moving picture machines, in combination with the frame thereof, having a film opening and a gate therefor, a friction roller 85 mounted in bearings on said machine frame adjacent the film opening, a rotary permanent magnet journaled on said machine frame and having a driving connection with said friction roller, an armature drum concentric with but in spaced relation over said magnet, an electric circuit including an electromagnet, means operated by said armature for opening and closing said circuit, and means operated by said electromagnet for 90 raising and lowering said gate.

2. In a fire trap operating means for moving picture machines, in combination with the frame thereof having a film opening and a gate therefor, friction roller means on 100 said machine frame in proximity to said film gate, a shaft carrying said roller means, bearings for said shaft, a second shaft in axial alignment with said first shaft, a rotary permanent magnet fixed on said second 105 shaft, a yielding torsion connection between said shafts, a drum armature concentric but in spaced relation to said permanent magnet, means for supporting said armature on said machine frame with the 110 axis thereof in alignment with the said second shaft, an electrical circuit including an electromagnet, means for connecting the film gate and the armature of said electromagnet, and a yielding means carried by 115 said drum armature for opening and closing said electrical circuit.

3. In a fire trap operating mechanism for moving picture machines, in combination with the frame thereof having a projection 120 opening and a fire gate therefor, a shaft journaled on said machine frame, a pair of friction rollers fixed on said shaft and adapted to frictionally engage the opposite margin of the film, a second shaft journaled 125 on said frame, a coil torsion spring connecting said first and second shafts, a permanent multi-polar magnet fixed on one end of said shaft, a third shaft journaled on said frame, an armature drum concentric with, 130

but in spaced relation to said permanent magnet, a spiral spring surrounding said third shaft and having its inner end fixed thereto, an electrical contact member at the 5 outer free end of said spring, a contact on said machine frame but insulated therefrom and arranged in the path of movement of said spring carried contact, an electrical circuit adapted to be closed by said contact and including an electromagnet, and means 10 for connecting the armature thereof with said film gate.

In testimony whereof I affix my signature.

ROY M. FORSYTH.
